US0D1008884S

(12) **United States Design Patent** (10) Patent No.: **US D1,008,884 S**
 (45) Date of Patent: ** Dec. 26, 2023

(54) **BICYCLE FRAME**

(71) Applicants: **GALAXY BICYCLE CO., LTD.**,
 Heshan (CN); **RALLY (GUANGZHOU) EBIKE CO., LTD.**,
 Guangzhou (CN)

(72) Inventor: **Zijie Yang**, Anlu (CN)

(73) Assignees: **GALAXY BICYCLE CO., LTD.**,
 Hesan (CN); **RALLY(GUANGZHOU) EBIKE CO., LTD.**, Guangzhou (CN)

(**) Term: **15 Years**

(21) Appl. No.: **29/824,246**

(22) Filed: **Jan. 24, 2022**

(51) LOC (14) Cl. **12-11**

(52) U.S. Cl.

USPC **D12/111**
